UNITED STATES PATENT OFFICE.

HERMAN VAN ORMER, OF HARTFORD, CONNECTICUT, ASSIGNOR TO LIBERTY MANUFACTURING COMPANY, OF PITTSBURG, PENNSYLVANIA, A CORPORATION OF PENNSYLVANIA.

ROTARY MOTOR.

969,010.

Specification of Letters Patent. Patented Aug. 30, 1910.

Application filed November 12, 1907. Serial No. 401,820.

To all whom it may concern:

Be it known that I, HERMAN VAN ORMER, of Hartford, Hartford county, Connecticut, have invented a new and useful Improvement 5 in Rotary Motors, of which the following is a full, clear, and exact description, reference being had to the accompanying drawings, forming part of this specification, in which—

10 Figure 1 is a longitudinal section of a motor embodying my invention, the section being taken on the irregular line I—I of Fig. 3; Fig. 2 is an end view of the admission head taken from its inner side; Fig. 3 is a cross section on the line III—III of Fig. 1; and Fig. 4 is an end view of the exhaust head looking at the inner end thereof.

15 My invention has relation to rotary motors, and more particularly to a motor for operating small tools, such as boiler tube cleaning tools, in which the motor is carried through the tube to be cleaned with the tool, although it may be used for various 20 other purposes.

25 The invention is particularly designed to provide a motor which shall be of simple and compact construction; which shall be capable of a high speed of operation, and 30 which may be operated by compressed air, although other fluid motive power may be employed.

35 Referring to the drawings, the numeral 2 designates the cylinder of the motor, having 35 therein an eccentrically located piston chamber 3.

40 4 is the piston shaft, which extends eccentrically through the chamber 3, and which carries the blades 5.

45 Formed in the wall of the cylinder 2 is a longitudinally extending admission port 6, which communicates with the piston chamber 3 by a plurality of cross-ports 7.

50 8 is a longitudinally extending exhaust port also formed in the thickened wall of the cylinder 2 and communicating with the piston chamber 3 by the plurality of cross-ports 9. The ports 6 and 9 preferably extend the entire length of the cylinder, whose otherwise open ends are closed by the heads 10 and 11. The head 10 preferably constitutes the admission head, and is formed with an interiorly threaded extension 12 designed to be connected with a pipe or hose

which supplies the motive fluid. This head 55 is provided with an inlet port 13, which leads to the end of the admission port 6. The exhaust head 11 is formed with a port or opening 14, which communicates with the exhaust port 8, and through which the 60 motive fluid is exhausted.

The heads are suitably secured to the cylinder by means of screws or dowels, the holes and location of which are indicated at 15^a in Figs. 2, 3 and 4. In the admission 65 head 12 is a sleeve or bushing 15, which forms the bearing for one end of the piston shaft 4, and in the exhaust head 11 are the bushings 16 and 17, which constitute the 70 bearings for the other end portion of said shaft, the shaft being extended through these bearings as indicated at 18 for connection with the tool to be operated. The bearing portions of the shaft are reduced, thereby forming the thrust shoulders 19, 75 which by contact with the inner ends of the bushings 15 and 16 serve to take up the thrust of the shaft in operation, said shaft also has a shoulder engagement at 20 with the inner end of the bushing 17.

80 Seated between the rear end of the shaft 4 and the thrust plate 21 in the admission head are a series of antifriction balls 22, which also form a thrust bearing for the 85 shaft.

85 The operation is as follows: Compressed air or other motive fluid being admitted to the port 13, passes into the port 6 and enters the piston chamber through the cross-ports 7. The motive fluid exhausts through 90 the cross-port 9 into the exhaust port 8 and out at the port 14. Where the motor is used for operating a boiler tube cleaning tool, the entire motor is carried through the tube with the tool, and this exhaust may be advantageously utilized in blowing out the material loosened by the tool.

95 The advantages of my invention result from the simplicity of the construction of the motor as a whole, and in the arrangement of the parts, whereby they may be quickly and readily assembled and be readily removed to permit renewal or repairs. The motor is extremely compact in form, and can be constructed in such small 105 sizes as to be adapted for use in boiler tubes of relatively small diameters.

100 Various changes may be made in the de-

tails of construction and arrangement by those skilled in the art, without departing from the spirit and scope of my invention.

I claim:-

5. 1. In a motor, a cylinder having a piston chamber therein and also having longitudinally extending admission and exhaust ports in its walls which communicate with said chamber at a plurality of different points, 10 the centers of said ports being less than 180° from each other, ported heads detachably secured to and closing the ends of the cylinder, and a rotary piston journaled in said heads and having a single slot extending 35 diametrically therethrough to seat a piston blade, substantially as described.
15. 2. In a motor, a cylinder having a piston chamber therein, with circumferential admission and exhaust ports communicating therewith, the center of said ports being less than 180° from each other in one direction, 20 the cylinder having heads provided with bearings for a piston shaft, and a rotary piston journaled in said heads and having 40 a single slot extending diametrically therethrough to seat a piston blade, substantially as described.
25. 3. In a motor, a cylinder having a piston chamber therein, with circumferential admission and exhaust ports communicating therewith, the center of said ports being less than 180° from each other in one direction, 20 the cylinder having heads provided with bearings for a piston shaft, and a rotary piston journaled in said heads and having 40 a single slot extending diametrically therethrough to seat a piston blade, substantially as described.
30. 4. In a motor, a cylinder having a piston chamber therein, with circumferential admission and exhaust ports communicating therewith, the center of said ports being less than 180° from each other in one direction, 25 the cylinder having heads provided with bearings for a piston shaft, and a rotary piston journaled in said heads and having 50 a single slot extending diametrically therethrough to seat a piston blade, substantially as described.

In testimony whereof, I have hereunto set my hand.

HERMAN VAN ORMER.
